Primary Examiner—Dominic Simone(74) *Attorney, Agent, or Firm*—Sterne, Kessler, Goldstein & Fox PLLC.(57) **CLAIM**

The ornamental design for a shoe upper, as shown and described.

DESCRIPTION

FIG. 1 is a left side elevational view of a shoe upper showing my new design;

FIG. 2 is a right side elevational view thereof;

FIG. 3 is a top plan view thereof;

FIG. 4 is a front elevational view thereof; and,

FIG. 5 is a rear elevational view thereof.

The broken line showing of a shoe sole in the Figures is environmental and forms no part of the claimed design.
